UNITED STATES PATENT OFFICE.

GEORGE A. LIPPINCOTT, OF PHILADELPHIA, PENNSYLVANIA.

STRIKER PLATE FOR GOLF CLUBS.

1,423,341.

Specification of Letters Patent. Patented July 18, 1922.

Application filed August 4, 1921. Serial No. 489,791.

To all whom it may concern:

Be it known that I, GEORGE A. LIPPINCOTT, a citizen of the United States, residing at Chestnut Hill, Philadelphia, in the county 5 of Philadelphia and State of Pennsylvania, have invented new and useful Improvements in Striker Plates for Golf Clubs, of which the following is a specification.

This invention relates to improvements in 10 golf clubs and striker plates therefor.

Heretofore it has been proposed to face with, or insert in the face of golf clubs, particularly wooden clubs, and in some instances, metal ones, materials which, it has 15 been claimed, would give a better grip on the ball for accuracy; greater density and more resistance to impact for increased distance; which would be immune to atmospheric changes; have better wearing qualities 20 so as to maintain a true striking face under continued use; and with some of the materials used, which would, by contrast in appearance between the facing material and the material of the body of the club, indicate 25 the proper point of impact on the face of the club.

Among the materials now in use may be mentioned iron, steel, celluloid, glass, ivory, and phenolic condensation products.

30 I have discovered a natural product, which, because of certain physical properties which it possesses, and which will be set forth hereinafter, is, according to experiments conducted by me, peculiarly fitted for and useful in making striker plates 35 for golf clubs.

This product is the hard shell of certain 40 of the Mollusca, among which may be mentioned the shell of the abalone, and particularly 45 that portion of the shell of mollusks known as "nacre," which is usually the inner surface of the shell, and is a calcareous concretion, deposited in wavy, although generally parallel, laminae; built up successively 50 in the growth of the shell until a considerable thickness, in the larger types of mollusks at least, is reached. It will be understood that only those types of mollusks 55 are suitable which are relatively non-brittle and have sufficient thickness to insure against breakage of the shell when the same comes in contact with the ball. Practically, all types of shell with which I have experimented have been found to be satisfactory, 60 only those shells being clearly unsuitable which have a relatively large proportion of

calcium carbonate with respect to the other organic matter.

This material, and particularly the nacreous deposit, is of dense formation; its specific gravity is high; it has a high fracturing point; it is impervious to atmospheric changes, and it has on the surface of its laminae minute corrugations, it being well known that it is such corrugated formation 65 which causes the iridescence which appears on its outer surface, this action of light on corrugated or striated surfaces being well known.

The qualities named, therefore, make 70 this material an exceedingly useful one for the purpose herein disclosed. Its density makes it highly resistant to impact. Its high fracturing point eliminates the likelihood of breaking. Its low coefficient of expansion makes it practically unaffected by atmospheric changes. Its weight or specific 75 gravity lends itself to the balancing of the club, and the striated formation referred to gives it an ideal gripping surface, for holding the ball.

In addition, it is non-porous or non-cellular so that it does not absorb moisture or take up dirt and become begrimed, and its iridescent qualities make it particularly 85 useful as a mark to define the proper striking area of the club.

The drawing herewith is illustrative of one physical embodiment of the invention, but it will be understood that this is merely 90 illustrative, and in no sense restrictive, as the material may be adapted to different styles of clubs and applied in ways other than that shown here.

In the drawings:

95

Fig. 1 is a perspective view of the head of the golf club with a striker plate of one form applied thereto.

Fig. 2 is a sectional view of the head of the club through the striker plate on substantially the line 2—2 Fig. 1.

Fig. 3 is a perspective view of one form of striker plate.

Fig. 4 is a side view of the plate or block shown in Fig. 3, illustrating conventionally 105 the laminated formation.

Referring to the drawings by numbers, like numbers indicating like parts in the several views, 10 denotes the head of a golf club, the particular head shown being the 110 head of a driver. Secured to the striking face of the head 10 is the striker plate 11,

and while this plate may be variously formed and attached to the head in different ways, in this particular instance, it is shown as being mounted in a recess or socket in that head.

The plate or block is shown in Fig. 3, and, as there shown, is made slightly tapering or wedge-shaped so that it may be driven home tightly in a correspondingly shaped socket in the head.

I prefer, although I do not confine myself to this, to fashion the block 11 by cutting a section from the shell, of the form desired, on lines substantially perpendicular to the laminae, with, preferably, the natural surface on the outer or striking face of the block. When cut in this manner the force of impact on the plate or block 11 is successively met by the series of laminations and from my present experiments the best results are obtained by fashioning the plate in this way.

Any of the usual means of attaching striker plates may be adopted, and in Fig. 1 the plate is held in its socket by means of any suitable adhesive, the recess in the head 10, or the sides of the striker block 11, or both, being coated with the adhesive, and the block then driven home. If desired, the bottom and side walls of the block to which the adhesive is applied may be rough dressed to furnish a better gripping surface for the adhesive.

In Fig. 2 the block is shown as being secured in its socket by means of pins 12, of any suitable material, which may be driven through holes drilled in the block 11. Either the pins may be used alone or they may be used in connection with the adhesive, if desired.

In fact, any of the usual methods of securing striker plates to the club head may be adopted, and, as stated, the striker plates may take any desired form and design other than that here shown.

In Fig. 4, the plate or block 11 has illustrated conventionally the laminae. The showing is conventional only, for while these laminae are clearly defined in the material, it is to be understood that the building up

of these laminae is such as to make a homogeneous material, there being nothing in the way of separation between the laminae which would be likely to cause splitting or cleavage of the material under impact.

55

It is to be understood that variations in form and design of the striker plate from the example here shown are within the range of my invention, and I do not confine myself to its use with any particular club, as it is adaptable to various forms of clubs.

I claim:

1. A striker plate for golf clubs formed of a suitably shaped section of the shell of a suitably thick and relatively non-brittle mollusk.

2. A striker plate for golf clubs formed of a suitably shaped section of the nacreous portion of the shell of a suitably thick and relatively non-brittle mollusk.

70

3. A striker plate for golf clubs formed of a suitably shaped section of nacre cut from the shell of the mollusk on lines substantially perpendicular to the laminae, to bring the laminations into substantial parallelism with the face of the plate.

4. A golf club having a striker plate of suitably thick and relatively non-brittle nacre.

5. A golf club having a recess in its striking face, and a suitably formed striker plate of nacre secured in said recess with its iridescent natural surface exposed.

80

6. A golf club having a recess formed in its striking face, and a suitably formed striker plate formed of a block of nacre of suitable shape and appreciable thickness, seated in and completely enclosed by said recess with its iridescent natural surface exposed.

90

7. A golf club having a recess formed in its striking face, and a suitably formed striker plate formed of a block of nacre of suitable shape and appreciable thickness, seated in and completely enclosed by said recess with its iridescent natural surface exposed and having its walls roughened.

In testimony whereof I have hereunto set my hand.

GEORGE A. LIPPINCOTT.
